INVENTOR.
Harry Budd,

1

A detailed line drawing of a butterfly, likely a swallowtail, shown from a dorsal perspective. Various parts of the butterfly are labeled with numbers: 11 for the forewing, 12 for the hindwing, 13 for the forewing base, 14 for the forewing apex, 15 for the forewing cell, 16 for the forewing margin, 17 for the forewing base, 18 for the forewing apex, 19 for the forewing cell, 20 for the forewing margin, 21 for the hindwing base, 22 for the hindwing apex, 23 for the hindwing cell, 24 for the hindwing margin, and 25 for the hindwing base. Below the butterfly, the word "BY" is written in capital letters. To the right of the butterfly, the word "INVENTOR." is written above the name "Harry Budd," and below the name, the word "ATTORNEY." is written above the signature of "Arthur C. Brown".

UNITED STATES PATENT OFFICE.

HARRY BUDD, OF INDEPENDENCE, KANSAS.

WASHING-MACHINE.

1,112,766.

Specification of Letters Patent.

Patented Oct. 6, 1914.

Application filed June 16, 1910. Serial No. 567,124.

To all whom it may concern:

Be it known that I, HARRY BUDD, a citizen of the United States, residing at Independence, in the county of Montgomery and 5 State of Kansas, have invented certain new and useful Improvements in Washing-Machines; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to a washing machine and has for its object to provide a device of that class in which articles may be cleansed with a minimum supply of water and without injury from friction with parts 20 of the apparatus.

It is a further object of my invention to provide a stationary receptacle within which the vessel containing clothes, or other articles, is adapted to revolve in a manner 25 to take up the water and force the same through the clothes with sufficient force to remove the dirt therefrom.

A further object of the invention is to provide the improved details of structure 30 presently described and illustrated in the accompanying drawings, in which:—

Figure I is a side elevation of a washing machine constructed according to my invention. Fig. II is a plan view of the body 35 of the machine, the box and cylinder covers being removed. Fig. III is a vertical section on the line III—III, Fig. I. Fig. IV is a vertical section on the line IV—IV, Fig. III. Fig. V is a detail view of one of the 40 cylinder rollers. Fig. VI is a perspective view of a portion of the cylinder, showing one of the intake mouths.

Referring more in detail to the parts: 1 designates the box, or outer receptacle, within 45 which the clothes cylinder is contained.

2 designates legs which are secured to the box 1 by suitable brackets 3 and elevate the same a desired distance from the floor.

50 Revolubly mounted within the box 1, by means presently described, is a cylinder C, comprising the solid end members 4, which are preferably of wood and have annular metal bands 5 on their inner faces, near their peripheries, the bands and end mem-

bers being provided with annular series of 55 alined apertures 6.

7—8 designate rollers which extend across the cylinder and have trunnion pins 7'—8' journaled in the annular series of alined apertures of the end members 4 and bands 60 5; the rollers 7 being of slightly greater diameter than the rollers 8 and alternating therewith around the cylinder, in order to provide a substantially corrugated inner surface, against which the clothes impinge, 65 and by means of which the travel of the clothes is retarded during the revolution of the cylinder.

Journalized in the sides of the cylinder, and extending thereacross, are the single inner 70 stop rollers 9, which are set in slightly from the outer rollers in order to further retard the clothes during the revolution of the cylinder, and prevent their sliding over the outer rollers and losing the rubbing effect 75 which the corrugated surface is adapted to produce.

Secured to the sides of the cylinder and projecting thereinto, are the baffle members 10 which are preferably of plano-convex 80 shape, as illustrated, and are adapted for engagement by the clothes, as the latter drop back to the bottom, after they have been raised by the revolution of the cylinder, thereby separating same, so that all of the 85 articles will be engaged by the corrugated surface. The end members 4 are provided with lid sections 4' which are hinged to the body portions to complete the cylinder ends, the bands 5 and rollers 7—8 being arranged 90 on the cover sections the same as on the body. Secured to the edges of these end members and inclosing the cylinder chamber, is the shell 11, which is preferably 95 formed of stiff galvanized iron.

At intervals throughout the periphery of the cylinder, the shell is slit transversely and circumferentially and the separated portion spread apart so as to provide the radial mouths 12, the edges of the outer 100 separated portions being turned back on wires 13' secured by eyes 13'' to the end members 4 to form the beads 13 and the edges of the inner separated portions being turned back on wires 14' secured by eyes 105 14'' to the end members 4 to form the beads 14 which add strength to the material, so that it will not be forced out of shape when

the machine is used. At the back of the radial mouths 12 the cylinder ends are provided with wedge shaped projections 4" formed integrally therewith and the shell material is laid on the inclined rear faces of the bosses to form hoods. At the ends of the radial mouths 12 the shell material provides straps 12' which are bent at the inner and outer edges of the said wedge shaped projections 4", so that they may fit against the front faces of said wedge shaped projections and form a facing therefor. Thus the shell is formed in a single piece with reinforced mouths at regular intervals when it is applied to the cylinder ends as described. It is apparent that the part of the shell which is secured to the cover sections 4' will form a continuation of the shell body to complete the perfect cylinder and may be provided with the mouths 12, the same as on the body portion.

15 designates latches which are attached to the cover of the cylinder and are preferably formed of strips of spring metal having apertures in their ends, through which studs 16, on the cylinder body, are adapted to project.

17 designates a bar which extends across the cylinder and is fixed to the ends of the latches 15, so that the latches on opposite ends of the cylinder may be lifted simultaneously.

In Fig. III, I show the cylinder journaled in the box 1, by means of the pins 18-19. The pin 18 is fitted in a squared socket in the cylinder bearing member 20 and revolvably mounted in the box bearing 21, and is held in its seat by means of a plate 22 on the inner face of the cylinder. On the outer face 40 of the other cylinder end, is a plate 23, having a threaded socket 24 within which the threaded end of pin 19 is seated. Pin 19 is projected through the side of the box 1 and has a tapered section journaled in a tapered bearing 25, which is set into the end of the box. On the outside of the box, pin 19 is provided with a gear wheel 26 which meshes with intermediate gears 27 and 28 which are driven from a crank wheel 29.

30 designates the box cover which is hinged at 31 and has a shoulder 32 which rests on the cross piece 33, on the front of the box, and may be secured in position by latches 34. The front of the box is turned outwardly and provided with a cross brace 35, to which a wringer may be secured. The out turned portion of the cylinder is inclined as shown in Fig. IV, in order that water from the wringer may drain back 60 into the box; the cross piece 33 being slightly raised in order to provide a passage way for the back draining water and to admit air into the apparatus. In the bottom of the box is an outlet 36, through which water 65 may be drained off. In using the machine,

a quantity of soaped water is placed in the box 1 and the cylinder filled with clothes, or articles which it is desired to cleanse. The cylinder and box covers are then fastened down and the cylinder revolved 70 through the crank and gear mechanism previously described. When the cylinder is revolved, water from the box is forced through the mouths 12 and between the rollers into contact with the clothes with sufficient force to cause it to pass through the fabric of the goods, thereby removing the dirt and stains therefrom. As the cylinder revolves, the uneven surface formed by the rollers of different diameter, causes the 80 clothes to be carried up above the center of the cylinder, so that the top articles may drop back and in turn be engaged by the rollers and contacted by the charge of soaped water; this elevating action being 85 made more positive by the stop rollers 9. When the clothes are carried above the center of the cylinder and dropped back, they strike the baffles 10, so that the mass is broken up and all of the articles are, some 90 time during the operation of the machine, brought into position for contact by the rollers and water jets. It is apparent that by forcing the soaped water through the fabric of the clothes, the dirt may be removed much more rapidly and with less 95 wear and injury to the articles, than when the dirt is removed by rubbing. It is also apparent that the clothes may be rinsed by the same process, as the jet of water taken 100 in through the mouths of the cylinder forces the water through the fabric of the goods, so as to remove all soap and dirty water. When the clothes have been cleansed and rinsed, the box and cylinder lids may be 105 opened and the articles fed directly from the cylinder to the wringer; the upper roller on the cylinder body revolving freely as the articles pass thereover and facilitating their removal from the machine.

Having thus described my invention, what I claim as new therein and desire to secure by Letters-Patent is:—

1. In a washing machine, a stationary box, a cylinder revolvably mounted in the box and comprising solid ends and a shell having outstruck portions forming shoulders, with the shoulders cut out to form radial mouths, and relatively large and small rollers revolvably mounted in the solid ends 115 and extending in a circle adjacent to but spaced from the shell, with large and small rollers alternating, substantially as set forth.

2. In a washing machine, a box, a cylinder revolvably mounted in the box and comprising solid circular ends, having radial shoulders, forming bosses on their peripheries, a shell mounted on the peripheries of the ends and bent over said shoulders, and 120 slit at the shoulders to form transverse 130

mouths, rods extending across the cylinder and fixed to the shoulders at inner and outer positions, with the slit portions of said shell turned about the rods to form beads, and 5 means for revolving the cylinder.

3. In a washing machine, a box, a cylinder revolubly mounted in the box and comprising solid circular ends, having radial shoulders forming bosses on their peripheries, a 10 shell mounted on the peripheries of the ends and bent over said shoulders, and slit at the shoulders to form transverse mouths, rods extending across the cylinder and fixed to the shoulders at inner and outer positions,

with the slit portions of said shell turned 15 about the rods to form beads, metal bands secured to the inner faces of said ends adjacent the shell and provided with registering apparatus, and rollers, having trunnion pins revolubly mounted in the apertures in 20 said bands.

In testimony whereof I affix my signature in presence of two witnesses.

HARRY BUDD.
